UNITED STATES PATENT OFFICE.

CHARLES L. DUNBAR, OF LEBANON, NEW HAMPSHIRE.

POWER EQUIPMENT FOR REVERSING-VALVES OF LOCOMOTIVE-ENGINES.

1,118,480.

Specification of Letters Patent. Patented Nov. 24, 1914.

Application filed June 4, 1914. Serial No. 842,869.

To all whom it may concern:

Be it known that I, CHARLES L. DUNBAR, a citizen of the United States, residing at 52 Elm street, Lebanon, county of Grafton, 5 State of New Hampshire, have invented certain new and useful Improvements in Power Equipments for Reversing-Valves of Locomotive-Engines, fully described and represented in the following specification and the 10 accompanying drawings, forming a part of the same.

This invention relates to an improved form of power equipment for reversing the valves of locomotive engines.

15 The invention employs an air or steam-cylinder with piston connected to a bell-crank for operating the valve-reversing link, and mechanism for controlling the operation of steam or air in such cylinder by means 20 of a main-distributing-valve and an auxiliary control-valve which latter is moved by the reverse-lever.

The object of the invention is not only to control the operation of the power-reversing 25 mechanism, but to combine with the reverse-lever or control-mechanism a locking device adapted to automatically lock the power piston-rod in any position to which it is moved, and thus prevent the bell-crank from 30 being accidentally shifted.

The nature and operation of the invention will be understood by reference to the annexed drawing, in which—

Figure 1 is an elevation of the reverse- 35 lever and its attachments with part of the rods which connect it with the reversing gear; Fig. 2 is a side view of the same; Fig. 3 a side view of the latches enlarged; Fig. 4 is a longitudinal section of the reversing- 40 cylinder and its valve and piston-connections in their central position; Fig. 5 is a similar section with the valve and connections at one end of their movement; Fig. 6 is a plan of the valve-seat on the power- 45 cylinder; Fig. 7 shows the under side of the cylinder distributing-valve; Fig. 8 shows the under side of the control-valve; and Fig. 9 is a diagram showing all the mechanism suitably connected.

50 The power-cylinder A is placed intermediate to the reversing bell-crank B and the reversing-lever C, and has its piston-rod D connected by a jointed tie-bar E to one arm of the bell-crank.

55 The moving of the reversing-lever actuates the power-piston by the following

means. The steam-chest F of the cylinder A is provided with a valve-seat a having steam-ports d, d, and an exhaust-port connected to an outlet c'. The main or distributing-valve G has two steam-ports b and an exhaust-port c, extended through its entire thickness.

The control-valve H is of the ordinary D-valve type, but has its exhaust-chamber e 65 formed with diamond-shaped ends, as shown in Fig. 8, to open the exhaust-connection gradually.

When the main-valve G is in its central position, as shown in Fig. 4, the ports d 70 stand over the ports b, b, but the ports d are sloped in each direction upon the under side so as to maintain connection with the ports b, b in every position of the main-valve G.

The length of the control-valve H is, in practice, one-sixteenth of an inch less than the length over the ports d, so that in the central position, shown in Fig. 4, each of such ports is open one-thirtieth of an 80 inch, thus permitting the fluid under pressure to operate equally at each side of the piston D', and thus produce no movement of the piston.

The valve-rod H' of the control-valve H 85 is actuated by connection to the reverse-lever C, through a connecting-rod C' and a control-lever I, which lever gives a great leverage to the reversing-lever and thus enables it to easily move the control-valve.

The valve-rod G' of the main-valve G is operated by a connection to the piston-rod D of the power-cylinder, through a main valve-lever J and a bar J' connected to the head E and to the bell-crank B, the lever J 95 reducing the movement so that the movement of the piston D' at each side of its central position produces a movement of the main-valve corresponding to the movements of the control valve.

100 With this construction, if the reversing-lever C be moved in either direction the control-valve is shifted and one of the ports d is closed and the other opened. The piston D' will then travel toward the end of the cylinder A, and by its direct connection with the main valve-rod G' moves the main-valve G beneath the control-valve H until the ports d are equally covered by the control-valve, and the pressure upon opposite 110 edges of the piston D' then becomes again equalized and its motion stops.

Without any further mechanism, the apparatus is destitute of any lock, as no connection exists between the bell-crank B and the reversing-lever, and the locking of the reversing-lever upon its segment C² by means of the latch f exerts no control over the movement of the bell-crank. The present invention, however, provides a connection between the reverse-lever and the bell-crank through the medium of an additional latch g upon the reverse-lever, and a hinged sector K having a notch g' to engage such latch, and curved seats at opposite sides of the notch to support the latch when the reverse-lever is first moved. The sector is connected by a jointed rod L to the lever J and thus through the bar J' to the bell-crank B. The locking of the sector thus locks the bell-crank B. The sector K is jointed upon the fulcrum M of the reversing-lever, and the connecting-rod L is jointed to the sector upon a pin N, equi-distant from the fulcrum M with the pin O to which the rod C' is connected for actuating the control-valve H.

The connection of the sector with the reversing-lever is such that when the reverse-lever is unlatched to move it over the segment C², the latch g is simultaneously released from the sector, leaving the reverse-lever free to move without any effect upon the sector. This is accomplished by making a spring-connection between the latch g and the slide f' of the latch f, which is actuated by the ordinary handle h.

The slide f' is provided adjacent to the latch g with the slotted cheeks i, and the latch g is provided with a transverse pin j fitted movably to such cheeks, and is pressed normally downward by a spring k, so that when the latch engages the notch of the sector K the pin lies in the bottom of the slots, and the lifting of the slide, when the handle h is operated to retract the latch f, also lifts the latch g from the sector. The latch is made a trifle shorter than the latch f, so as to fully clear the notch g' before the lever C is released from the segment C².

When the reverse-lever is moved over its segment C² and locked thereon, the latch g is released from the lifting action of the pin j and rests upon the curved surface of the sector K, under the pressure of the spring k. The movement of the power-piston D', which results from such movement of the reverse-lever, then moves the lever J, the rod L and the sector K; placing the latter in the same relation to the reverse-lever as before moving, and thus permitting the latch g to lock the sector. The sector thus becomes locked in any position to which the reverse-lever may be moved, and the bell-crank B is thus immovably held by its connection to the lever J, the rod L and the sector.

The levers I and J are so proportioned as to respectively reduce the motion of the control-valve and the main-valve in the same proportion during corresponding movements of the reversing-lever and the piston D', thus securing the coincidence of the notch in the sector with the auxiliary latch, after each movement of the reversing-lever and resulting movement of the piston.

By this mechanism, the bell-crank B may be shifted to either end of its stroke, thus shifting the reverse-link of the locomotive engine-valve so as to reverse the same with full movement; or the bell-crank may be shifted in any intermediate degree, by a lesser movement of the reverse-lever C, as the movement of the power-piston D' is arrested when it has moved the main-valve into an equalizing or neutral position below the control-valve. In whatever position the bell-crank B is moved, it is positively locked and immovably held by the engagement of the latch f with the segment C², and of the latch g with the sector K.

While the invention is primarily designed for reversing the position of the bell-crank B and the link-mechanism connected therewith for reversing an engine-valve, it is obvious that it is adapted to lock any power-operated mechanism in the position to which it may be moved by the agency of a control-valve and a reverse-lever.

In Fig. 9 of the drawing, the outline of the locomotive boiler is diagrammatically represented by a dotted line P, and the levers I and J are shown mounted upon the boiler by fulcrum-plates Q; but it is immaterial to the operation of the essential elements whether the apparatus be constructed exactly as shown, as fulcra for the levers I and J may be mounted upon a support different from the locomotive boiler, if the apparatus be used for some different purpose.

Having thus set forth the nature of the invention what is claimed herein is:

1. In a power-reversing mechanism, the combination, with a power-cylinder, and a piston with rod to transmit the power, of a valve controlling the supply of fluid under pressure to such cylinder, a reversing-lever connected to such control-valve, and a locking-device comprising an auxiliary latch upon the reverse-lever and a sector movable with the moving power-device and adapted to engage such latch.

2. In a power-reversing mechanism, the combination, with a power-cylinder, and a piston with rod to transmit the power, of a distributing-valve applied to the ports of the cylinder and having the ports extended through its thickness, and actuated by a connection to the piston-rod, a control-valve applied to the ports upon the distributing-valve and a reversing-lever connected

to such control-valve and having a latch and segment for locking the same, a notched sector adjacent to the reverse-lever and movable with the piston-rod, and an auxiliary 5 latch upon the reverse-lever for locking such sector and holding the piston positively in its adjusted position.

3. In a power-reversing mechanism, the combination, with a power-cylinder, and a 10 piston with rod to transmit the power, of a valve controlling the supply of fluid under pressure to such cylinder, and a reversing-lever connected to such control-valve, and having a notched segment and a main- 15 latch to engage the same, a notched sector adjacent to the reverse-lever, a connection from the same to the piston-rod, and an auxiliary latch upon the reverse-lever having a spring-connection with the main- 20 latch and adapted to press elastically upon the sector and engage the notch therein when the sector is moved by the piston-rod.

4. In a power-reversing mechanism, the combination, with a power-cylinder, and a 25 piston with rod to transmit the power, of a valve controlling the supply of fluid under pressure to such cylinder, and a reversing-lever connected to such control-valve and having a notched segment and a main- 30 latch to engage the same, a sector hinged upon the reverse-lever fulcrum and having a central notch with curved seat at each side of the notch and connected to move with the piston-rod, and an auxiliary latch hav-

ing a spring-connection to the main-latch 35 and adapted to engage the notch in the sector, or to rest upon the curved seats when the reverse-lever is moved independent of the sector.

5. In a power-reversing mechanism, the 40 combination, with a power-cylinder, and a piston with rod to transmit the power, of a main distributing-valve having a valve-rod, and a lever connecting the same to the piston and proportionally reducing the valve 45 motion, a control-valve applied to the ports of the main-valve, and having a valve-rod and a reducing-lever corresponding to the main valve-lever, a reversing-lever having a pin-and-rod connection to the control-lever, and a notched segment and a main latch to engage the same, a notched sector hinged upon the reverse-lever fulcrum and having a pin-and-rod connection to the main 50 valve-lever, and an auxiliary latch actuated by the main latch to engage the sector, the proportions of the levers and connections operating to bring the notch of the sector coincident with the auxiliary latch when the piston is moved after each actuation of 55 the reverse-lever.

In testimony whereof I have hereunto set my hand in the presence of two subscribing witnesses.

CHARLES L. DUNBAR.
